THE COLUMBIA PLANOGRAPH CO., WASHINGTON, D. C.

UNITED STATES PATENT OFFICE.

MICHAEL E. LEARY AND WILLIAM HINCHLIFFE, OF HUNTSVILLE, ALABAMA.

DEVICE TO FACILITATE TYING OF SPINDLE-BANDS.

1,181,899.

Specification of Letters Patent.

Patented May 2, 1916.

Application filed January 15, 1916. Serial No. 72,294.

To all whom it may concern:

Be it known that we, MICHAEL E. LEARY and WILLIAM HINCHLIFFE, citizens of the United States, residing at Huntsville, in the 5 county of Madison and State of Alabama, have invented certain new and useful Improvements in Devices to Facilitate Tying of Spindle-Bands, of which the following is a specification.

- 10 This invention is a simple and easily manipulated device by the use of which the operator may apply the driving band or belt to the whorl of a spindle with any desired degree of tension.
- 15 At the present time, so far as we are aware, it is the practice to join the ends of the driving band or belt at a point below the whorl of a spindle which point is at a less distance from the driving pulley or cylinder than the 20 surface of the whorl around which the belt passes in the operation of the spinning machine. As a result of this practice, when the belt is slipped over and onto the whorl the tension of the belt is increased so that an 25 unnecessary strain is placed on the belt and on the spindle causing excessive wear upon the belt and other parts of the spinning machine and also causing great loss of power in driving the spinning machine.
- 30 This invention provides an apparatus which may be readily applied to and removed from the spindle of any spinning machine and by the use of which the belt may be tied with any desired tension and 35 easily fitted to the spindle whorl. When the belt so tied is fitted to the spindle whorl, it will drive the same with just the proper tension needed for the particular construction of the machine and the work to be done and 40 will not pull the spindle out of its perpendicular position so that the product of the machine will be uniform in quality and wear upon the spindle and its parts will be 45 reduced with a corresponding increase in the durability of the spindle.

The invention is illustrated in the accompanying drawings and will be hereinafter fully described, the novel features being subsequently particularly pointed out in the 50 claims following the description.

In the drawings: Figure 1 is a plan view of a spindle and its mounting showing our improved device fitted thereto; Fig. 2 is a similar view, the latch being omitted and a 55 portion of the oil cup being broken away;

Fig. 3 is a perspective view of our improved device; Fig. 4 is an end view of the device showing so much of the spindle and its mounting as will aid in an understanding of the operation of the invention.

The spindle 1 may be of any preferred construction and is equipped with the usual whorl 2 and mounted in the rail 3 in the ordinary manner.

In carrying out our invention, we employ 60 a substantially U-shaped frame comprising an upper plate 4, a lower plate or arm 5 and a standard or connecting plate 6 which spans the space between the upper and lower plates and joins the same as clearly shown 65 in the drawings. The upper plate or arm 4 is provided with a notch 7 in its free end or edge which is adapted to fit around the upper end of the bracket or bearing 8 in which the spindle is mounted while the 70 lower arm or plate 5 is provided with a longitudinal slot 9 adapted to fit over the lower end of said bracket or bearing. Upon the outer side of the bridge or connecting plate 6 we pivot the latch or locking arm 10 75 which depends from its pivot 11 and is then turned inwardly at an angle corresponding to the angle between the members 5 and 6 thereby providing a bearing arm 12 having its free end arranged to bear against 80 the lower end of the bearing or bracket in which the spindle is mounted, as shown most clearly at 13 in Fig. 2. Upon the upper side of the top plate 4 is slidably mounted a yoke 14, the arms of which are disposed at opposite 85 sides of the spindle and the whorl upon the same. These arms 15 are tapered at their extremities, as shown at 16, whereby they will offer no obstruction to the movement of the belt or band in placing the same in position. The head or transverse member 17 of 90 this yoke is extended vertically and at one side is constructed with an overhanging finger 18 which is adapted to engage over the belt while the same is being tied. Upon the 95 side of this expanded head of the yoke is fulcrumed the releasing lever or cam 19 which has one face grooved, as indicated at 20, or otherwise constructed to engage the belt and retain the same in position while 100 the ends are being united. This cam or releasing lever normally occupies the position shown in Figs. 1, 2 and 3, and in dotted lines in Fig. 4, so that the branches or members of the belt will be retained in such po- 105

110

sition that the ends may be easily united. After the ends of the belt have been joined, the outstanding arm or handle member 21 of the lever is swung up to the position shown in full lines in Fig. 4, thereby turning the groove 20 into a substantially vertical position and lifting one side or run of the belt over the yoke, whereupon the tension or strain to which the belt has been subjected during the tying operation will pull the belt over and into the groove of the whorl 2, as will be readily understood. A lug 22 depends from the head 17 of the yoke through a slot 23 in the plate 4 and the lower end of this lug is secured to one end of a bolt 24 which is slidably mounted in a housing or bracket 25 secured to the underside of said plate. The bolt is guided in its movement by the standard 6 and a guide 26 provided on the under side of the plate 4, and a spring 27, disposed within the housing, bears upon the bolt so as to hold the same normally in its outermost position. It will be readily understood that, when the ends of the belt are brought around the yoke 14 and are tied together, the belt will exert a pull upon the yoke in opposition to the tension of the spring 27 and the operator can readily adjust the tension of the belt by pulling upon the same so that it will overcome the tension of the said spring to a greater or less degree. The belt can thus be set so as to exert any desired tension upon the whorl and, consequently, will be adapted to light or heavy work as circumstances may demand. In order that the operator may have a definite knowledge of the tension to which the belt has been set, we provide an indicator or pointer 28 which is secured upon the outer end of the bolt 24 and projects therefrom over the upper plate 4 as clearly shown in the drawings, a series of graduations 29 being marked in any convenient manner upon the upper surface of the plate 4 according to predetermined calculations so that the end of the indicator or pointer will show by its position the degree of tension to which the belt has been set.

It is thought the use and advantages of our improved device will be readily understood from the foregoing description taken in connection with the accompanying drawings.

The spindle is mounted in the usual or any preferred manner and the belt, indicated by dotted lines at 30 in Fig. 1, is passed around the driving pulley or cylinder and its ends brought around the yoke 14, with the side members or runs of the belt engaging the grooves 20 in the cam or lever 19, and passes through the space between the overhanging finger 18 and the adjacent side member of the yoke, the base or inner wall of said space being beveled, as indicated

most clearly at 31 in Fig. 4, so as to prevent cutting or unnecessary wear upon the belt. In fitting our improved device to the spindle, the locking member 10 is swung to the position shown in Fig. 3 thereby pulling the arm 12 out of the plane of the spindle and its bearings so that the device may be tilted sufficiently to permit the longitudinal slot 9 to be engaged over the lower end of the spindle bracket or bearing. The device is then swung upwardly so that the notch 7 will pass around the upper end of the bracket just below the whorl, as is shown in Fig. 2. When the belt, therefore, is drawn around the outer side of the yoke 14 it will be substantially in the horizontal plane of the groove of the whorl so that, when the belt is released from the yoke, it will pass directly into its operative engagement with the whorl. After the device has been fitted in position, as just described, the locking arm 12 is swung into the vertical plane of the U-shaped frame consisting of the members 4, 5 and 6, and will lie directly under the lower plate 5, as shown in Figs. 2 and 4, so as to bear against the lower end of the spindle mounting and thereby prevent tilting of the device. After the belt has been fitted and released by manipulation of the lever 21 and cam 19, as heretofore stated, the arm 12 is again swung to the position shown in Fig. 4 whereupon the device will readily tilt downward and outward so as to be released from the spindle mounting. The spinning machine may then be operated in the usual manner.

It will be readily noted that we have provided an exceedingly simple device which may be easily applied to or removed from any spindle and by the use of which the belt may be easily and quickly tied and engaged around the whorl.

Having thus described the invention, what is claimed as new is:

1. An apparatus for the purpose set forth comprising a supporting frame constructed to engage a spindle mounting, means for locking said frame to said mounting, means on said frame to engage a belt while the ends of the same are being united, and means for releasing the belt after the ends are united to permit the same to engage a spindle whorl.
2. A device for the purpose set forth comprising means to support a belt in the plane of a spindle whorl, means for retaining the side members of the belt in said plane while the ends of the belt are being tied, and means to release the belt from said retaining means after the ends are tied.
3. In an apparatus for the purpose set forth, the combination of means for supporting the runs of a belt in the plane of a spindle whorl and retaining the same in said plane while the ends thereof are being tied, means for releasing the belt from said means

after the ends are tied, and means for yieldably holding the said belt-retaining means away from the spindle whorl.

4. In a device for the purpose set forth, the combination of means for engaging the runs of a belt while the ends of the same are being united, means for releasing the belt after the ends are united, means for yieldably holding said belt-engaging means 10 in a retracted position, and a tension indicator coöperating with said yieldable means.

5. A device for the purpose set forth comprising a frame adapted to detachably engage a spindle mounting, means for locking said frame to said mounting, a belt-engaging member on said frame adapted to hold the runs of a belt while the ends thereof are being united, and means for releasing the belt from said retaining means 20 after the ends are united.

6. In a device for the purpose set forth, the combination of a frame having upper and lower members, the lower member being constructed to fit around the lower end of a spindle mounting and the upper member being constructed to engage the upper end of said mounting, a locking arm mounted upon the frame and adapted to bear 25 against the spindle mounting to retain the frame thereon, a belt-retainer mounted upon said frame, and means for releasing the belt from said retainer.

7. In a device for the purpose set forth, the combination of a frame having a lower member provided with a longitudinal slot adapted to engage around the lower end of a spindle mounting and having its upper member provided with a notch in its end 35

adapted to engage the upper end of the 40 spindle mounting, a locking arm pivotally mounted upon the said frame and having its free end arranged to bear against the spindle mounting to retain the frame thereon, a belt-retainer fitted on said 45 frame, and means for releasing the belt from said retainer.

8. In a device for the purpose set forth, the combination of a frame adapted to engage a spindle mounting, means for locking 50 said frame to said mounting, a belt-retainer slidably mounted on said frame, means for yieldably holding said retainer in its outermost position, and a cam pivoted upon said retainer and adapted to release the belt 55 therefrom.

9. In a device for the purpose set forth, the combination of a frame, a yoke mounted thereon and arranged to support the side runs of a belt at the sides of a spindle, 60 and a belt-releasing member mounted on said yoke and operable to transfer the belt from the yoke to the spindle.

10. In a device for the purpose set forth, the combination of a frame, a yoke mounted 65 thereon to support the side runs of a belt at opposite sides of a spindle, a finger on one side of said yoke engaging over one run of the belt, and a cam mounted on the yoke and having a belt-engaging groove in its 70 outer face, said cam being operable to effect transfer of the belt from the yoke to the spindle.

In testimony whereof we affix our signatures.

MICHAEL E. LEARY. [L.S.]
WILLIAM HINCHLIFFE. [L.S.]
